UNITED STATES PATENT OFFICE.

GEORGE H. JENNEY, OF CHICAGO, ILLINOIS.

DESIGN FOR A REFUSE-RECEPTACLE.

SPECIFICATION forming part of Design No. 35,372, dated December 3, 1901.

Application filed July 27, 1901. Serial No. 69,991. Term of patent 14 years.

To all whom it may concern:

Be it known that I, GEORGE H. JENNEY, a citizen of the United States, and a resident of Chicago, Cook county, State of Illinois, have invented and produced a new and useful Design for a Refuse-Receptacle; and I do hereby declare that the following is a specification thereof, reference being had to the accompanying drawing, and to the reference characters marked thereon, and in which the figure is a perspective view of a refuse-receptacle embodying my invention.

The refuse-receptacle embodying my design shown in the accompanying drawing consists in a rectangular body portion A, which is supported by means of straight vertical legs B, located at each corner and forming continuations of the vertical corner edges of the body portion. Braces b extend from either side of each of the legs to the under side of the body portion intermediate of the legs. The body portion is surmounted by a cover C, comprising two sides C', of trapezoidal shape, which extend in an inclined direction from the

straight horizontal tops of opposite sides of the body portion A to a common line, thereby forming a peak. The cover is completed by two ends C², of triangular form, extending directly from their bases in an inwardly-inclined direction from the straight horizontal tops of the opposite ends of the body portion to the peak of the cover, where their apexes terminate. An opening is provided at the top of each of the sides of the body portion, which is closed by an inwardly-swinging door d.

Having described my design, what I claim as new, and desire to secure by Letters Patent, is—

The design for a refuse-receptacle, substantially as shown and described.

In witness whereof I have hereunto subscribed my name in the presence of two subscribing witnesses.

GEO. H. JENNEY.
